UNITED STATES PATENT OFFICE.

WILLIAM H. ADSIT, OF BATAVIA, NEW YORK, ASSIGNOR OF ONE-HALF TO DANIEL W. TOMLINSON, JR., OF BATAVIA, NEW YORK.

CHANGE-SPEED-GEAR-OPERATING MEANS FOR MOTOR-VEHICLES.

1,292,413.

Specification of Letters Patent. Patented Jan. 28, 1919.

Application filed April 10, 1915. Serial No. 20,430.

To all whom it may concern:

Be it known that I, WILLIAM H. ADSIT, a citizen of the United States, residing at Batavia, in the county of Genesee and State of New York, have invented a new and useful Improvement in Change-Speed-Gear-Operating Means for Motor-Vehicles, of which the following is a specification.

This invention relates to operating or shifting mechanisms for the change speed gearing of automobiles or motor vehicles of the kind now in general use, in which a change speed gearing is employed between the engine and the driving wheels of the vehicle for reversing the motion of the vehicle and changing the gear ratio with which the engine operates the driving wheels.

In these motor vehicles as commonly constructed a hand operated gear shifting lever is employed for shifting the movable gear or gears of the change speed gearing for reversing the motion of the vehicle and changing the speed thereof. A clutch is also employed between the engine shaft, which turns always in the same direction, and the change speed gearing and this clutch is usually controlled by a pedal which is depressed to release the clutch and which is released to cause the clutch to couple the engine shaft with the drive gearing of the vehicle. The change speed lever has to be actuated manually to place the desired forward or reverse gearing in action while the clutch is held released by means of the clutch pedal.

One of the principal objects of this invention is to provide a practical and desirable operating mechanism for the change speed gearing by means of which the driver can, by the movement of a conveniently located selecting lever or device, set the mechanism for placing in action any desired change speed gearing and thereafter place the selected gearing into action by the operation of the clutch pedal. The operation of the selecting device does not shift the change speed gear but merely serves to select or determine the gear which is to be placed in action, the shifting of the change speed gear being thereafter effected by other means, preferably by the clutch operating spring under the control of the clutch pedal. In this way the driver can at any time, either while the vehicle is in motion

or at rest, select any desired one of the several speed gearings and thereafter place the selected gearing into action by the operation of the clutch pedal without having to shift the change speed gearing by hand 60 while holding the clutch pedal down to release the clutch, as is the case with motor vehicles as ordinarily constructed.

Other objects of the invention are to construct the mechanism so that the selecting 65 lever or device can be arranged on the steering column, where it can be readily reached and easily operated without removing the hands from the steering wheel; also to provide means whereby the movable gear 70 or gears of the change speed gearing can be shifted in opposite directions by like movements of the clutch pedal, thus adapting the mechanism to change speed gears in which the movable gear or gears are shifted in 75 opposite directions to place different speed gearings in action; also to construct the mechanism so that the selecting device can be moved for any desired selection of gears and returned to the neutral position, or to 80 any desired different selecting position, without necessitating the actuation of the change speed gear; also to construct the mechanism so that the clutch pedal can be actuated to control the clutch in the usual 85 manner without changing the setting of the selecting means; also to provide locking means for preventing the accidental simultaneous actuation of more than one of the gear shifting devices, and for preventing 90 the accidental release of the gear shifting devices from the operative shifting position; and to improve the mechanism in the various other respects hereinafter described and set forth in the claims. 95

In the accompanying drawings:

Figure 1 is a side elevation of a change speed gear operating mechanism embodying the invention, the casing of the change speed gear and a portion of the engine 100 casing being shown in outline to indicate the position of the mechanism relative to these parts.

Fig. 2 is a plan view thereof.

Fig. 3 is a plan view, on an enlarged 105 scale, of the operating mechanism, the casing therefor being shown in section in line 3-3, Fig. 4.

Fig. 4 is a sectional elevation thereof in line 4-4, Fig. 3. 110

Fig. 5 is a fragmentary sectional elevation of the gear shifting mechanism in line 5—5, Fig. 3, showing the dog engaged with the shifting gear for moving the latter.

5 Fig. 6 is a similar elevation, showing the position of the parts after the shifting movement thereof.

Figs. 7, 8 and 9 are fragmentary sectional elevations in line 7—7, Fig. 3, showing respectively the positions of the parts corresponding respectively to the positions shown in Figs. 4, 5 and 6.

Fig. 10 is a fragmentary plan view of the selecting mechanism, showing the selector cam in position for the actuation of the first shifting gear.

Fig. 11 is a detached perspective view of the retainer ring.

Fig. 12 is a sectional plan view in line 20 12—12, Fig. 7.

Fig. 12^a is a sectional plan view in line 12—12^a, Fig. 9.

Fig. 13 is a transverse sectional elevation of the shifting mechanism and a portion of 25 the change speed gearing, in line 13—13, Fig. 3.

Fig. 14 is a fragmentary sectional plan view in line 14—14, Fig. 15, of the actuating means for the selector cam.

30 Fig. 15 is a sectional elevation thereof in line 15—15, Fig. 14.

Fig. 16 is a sectional elevation of the shifting mechanism in line 16—16, Fig. 3, showing the second shifting gear with the 35 actuating dog engaged therewith ready to turn the gear.

Fig. 17 is a similar view, showing the shifted position of the parts.

Fig. 18 is a fragmentary side elevation of 40 the operative connections between the clutch pedal and the shifting mechanism.

Fig. 19 is a sectional elevation thereof in line 19—19, Fig. 18.

Fig. 20 is a side elevation similar to Fig. 45 18, showing the shifted position of the parts.

Fig. 21 is a similar side elevation, showing another position of the parts.

Fig. 22 is a plan view of the steering head.

A represents the casing of the change 50 speed gear, B a portion of the engine casing, C the steering column and D the clutch pedal of a motor vehicle, these parts being constructed and associated in the known manner employed in some makes of motor 55 vehicles. The change speed gear, a portion of which is indicated at E, Fig. 13, may be of any usual or approved construction and it is not shown or described in detail herein.

1 and 2 represent the two gear shifting 60 rods of the change speed gear. These rods are, as usual, arranged in the change speed gear casing to slide endwise in suitable guides or bearings, one of the guides for one of the rods being shown at 3, Fig. 4. The 65 shifting or operating mechanism is shown

in the drawings in connection with a change speed gear which gives three different speeds in a forward direction and a reverse motion of the vehicle, two of the speed gearings being placed in action by the movement 70 of one of the shifting rods, as 1, and the other two speed gearings being placed in action by the movement of the other gear shifting rod 2. The shifting or operating mechanism which actuates the gear shifting rods 1 and 2 is preferably inclosed in a housing or casing 4 which is bolted or otherwise removably secured on the open topped change speed gear casing A in place of the usual cover or top plate of the change speed 80 gear casing.

5 represents a rock shaft which extends transversely in the casing 4 above the gear shifting rods 1 and 2 and is journaled in suitable bearings 6 at the opposite sides of 85 the casing 4. Gear shifting wheels or gears 7, 8, 9 and 10 are mounted to turn freely on the shaft 5, there being in the construction shown four of these wheels, one for moving each of the gear shifting rods 1 or 2 in one direction for placing in action one of the gear trains of the change speed gear. Each of the gear shifting wheels has a series of gear teeth on one portion of its periphery and a notch 11 for the engagement of a dog 90 for turning the wheel, the remaining portion of the periphery of the gear being preferably cylindrical. 12 represents a yoke or dog-carrier which is secured to the shaft 5 to rock therewith and carries a series of 100 dogs or devices 13, 14, 15 and 16, adapted to be engaged with the gear shifting wheels 7, 8, 9 and 10, respectively, for causing the latter to turn with the dog-carrier and shaft 5. In the construction shown, see Figs. 3—10 105 and 13, the yoke is of substantially U-shape, having a cross bar or portion which extends substantially parallel with the shaft 5 adjacent to the peripheries of the shifting gears, and end legs provided with collars 17 which encircle the shaft 5 adjacent to its bearings and are secured thereto, as by pins 18. Each of the dogs 13—16 is arranged to slide toward and from the co-operating gear shifting wheel in a pocket 19, Figs. 5, 6 and 12, 115 in the cross bar of the dog-carrier, and each dog preferably has a spring-actuated bolt 20 arranged to slide in a guide pocket or recess 21 in the body of the dog into and out of the notch 11 in the co-operating gear shifting wheel. A pin 21^a extending through the dog, through a slot 22 in the bolt 20 and projecting at its ends into slots 23 in the upper and lower walls of the pocket 19 in the dog-carrier, retains the dog and bolt in 125 position and limits the movements of the dog and of the bolt. The dog is retracted or moved away from the co-operating gear shifting wheel by a suitable spring 24, conveniently located in a spring seat in the dog- 130

carrier and engaging a lug or ear 25 on the dog, and a spring 26, preferably confined in spring pockets in the dog and bolt 20, is provided for projecting the bolt 20 into the notch 11 of the coöperating gear wheel. As shown, the dogs are staggered, the alternate dogs 13 and 15 being disposed lower than the other dogs 14 and 16 for a purpose hereinafter explained, and for the sake of compactness of construction the springs 24 are located at the upper sides of the dogs 13 and 15 and at the under sides of the dogs 14 and 16. In the normal or neutral position of the parts, in which all of the gear trains of the change speed gear are out of action, the several dogs 13—16 are retained, as hereinafter described, in their retracted positions with the bolts 20 out of engagement with the gear shifting wheels 7—10, so that the dog-carrier can be rocked up and down with the rock shaft 5 without the dogs engaging and operating any of the gear shifting wheels. If the dog-carrier is swung downwardly and one of the dogs is moved toward the coöperating gear shifting wheel, the spring bolt 20 of such dog will be shoved back into the dog against the action of its projecting spring 25 by the retaining device hereinafter described until the bolt 20 of the dog-carrier is brought to a position opposite the notch 11 of the gear shifting wheel, when the bolt will spring into the notch 11 and connect the dog to the wheel so that when the dog-carrier is swung upwardly the gear shifting wheel will be turned therewith.

The dogs are adapted to be engaged or coupled with their respective gear shifting wheels by a selecting device 30 which is provided with a series of cam lugs or parts 31, 32, 33 and 34, each intended to engage the outer end of one of the dogs 13—16 for moving the dog toward its coöperating shifting gear. Each dog preferably has an end lug or reduced outer end having a beveled face 35 adapted to engage the coöperating cam of the selecting device for moving the dog inwardly, and with a flat end face 36 adapted to engage a corresponding flat end face 37 on the cam for holding the dog in its projected position. The selecting device shown consists of a sleeve which is pinned or otherwise secured on a flat faced bar 38 which is held from turning and arranged to slide parallel with the axis of the gear shifting wheels in suitable guide bearings 39 and 40 in the casing 4. When the selecting device is in the neutral or inoperative position, shown in Figs. 3 and 4, the several cams 31—34 are out of the vertical planes occupied by the coöperating beveled lugs of the several dogs. In this position of the parts the rock shaft and dog-carrier 12 can be rocked up and down without causing either of the dogs to engage and be moved by the cams

of the selecting device. If, however, the selecting device is moved, for instance, to the right, to the position shown in Fig. 10, the first cam 31 thereof will be placed in the vertical plane of the reduced end of the coöperating dog 13, so that if the dog-carrier is then swung downwardly the first dog 13 will engage the cam 31 and be thereby moved into engagement with the gear shifting wheel 7. In this position of the parts 75 the third cam 33, as shown in Fig. 10, is located below and in the vertical plane of the end lug of the second dog 14, but on account of the staggered arrangement of the dogs above explained, this dog will not engage 80 the cam 33 when the dog-carrier is swung downwardly, the movement of the dog-carrier not being sufficient to cause such engagement, and thus only the first dog 13 will be moved to engage the coöperating 85 gear shifting wheel 7. The cams 31—34 are staggered correspondingly to the dogs 13—16, so that the several dogs can be actuated by like movements of the dog-carrier when the selecting device is properly placed. 90

By moving the selecting device 30 an appropriate distance the second cam 32 thereof is brought into operative relation with the second dog 14, and by successive further movements of the selecting device the third 95 and fourth cams thereof can be placed in operative relation to the third and fourth dogs 15 and 16, respectively, so that the selecting device can by appropriate movements thereof be placed in position to actuate any one of the several dogs. In each operative position of the selecting device when one of the cams is in operative relation to the coöperating dog, another of the cams will be located in the vertical plane of another dog, but by reason of the described staggered arrangement of the dogs and cams, only one dog can be operated when the dog-carrier is rocked in any operative position of the selecting device. The described 100 staggered arrangement of the dogs and cams is desirable as it reduces the length of the selecting device and the distance which the selecting device has to be moved to operate the several dogs about one half and makes possible a much more compact construction. The selecting device is adapted 110 to be moved to a neutral or inoperative position between each two of its operative positions, in which all of the cams 31—34 are 115 out of the vertical planes of the reduced ends of the dogs so as not to operate any of the dogs if the dog-carrier is rocked while the selecting device is in such neutral position.

Fig. 4 shows the normal position of the dog-carrier and dogs; Fig. 5 shows the position thereof when the dog-carrier has been swung downwardly and the first dog 13 engaged with the first gear shifting wheel 7, 120 125 130

and Fig. 6 shows the position of the parts when the dog-carrier has been returned and has turned the first gear shifting wheel. Figs. 16 and 17 show the second gear shifting wheel and its dog in positions corresponding to those shown in Figs. 5 and 6, respectively.

The selecting device is shifted to place it in its several operative and neutral positions by suitable operating means which are preferably such that the selecting device is operated by a handle or lever which is mounted on the steering column where it is mounted on the steering column where it can be readily reached and moved by the driver without removing his hands from the steering wheel. As shown, the slide bar 38 which carries the selecting device 30 is provided at one end with rack teeth 41, see Figs. 14 and 15, which mesh with a pinion 42 which is secured to a shaft 43 journaled in a suitable bearing 44 in the upper portion of a divided box 45 which is detachably secured to the adjacent side of the casing 4 and serves to inclose the rack and pinion. A rock arm 46 is secured to the upper end of the shaft 43 and connected by a rod 47 and a rock arm 48 to a shaft 49 which is journaled in a suitable bearing supported on the engine casing at the base of the steering column and is connected by a pair of bevel gears 50 to a shaft 51 which extends axially through the steering column and is provided at its upper end with an operating handle or lever 52. The outer end of this handle 52 preferably swings adjacent to an arc-shaped plate or quadrant 53 which is secured to the steering column and is provided with suitable indicia to indicate the several positions of the selecting device. Thus by moving the handle 52 to the reverse, first, second or third speed position indicated on the quadrant 53, the selecting device 30 is correspondingly moved and placed in position for actuating the dog of the corresponding gear shifting wheel. Between each two of the four operative positions are indicated on the quadrant neutral positions, and by moving the handle 52 to any one of these neutral positions the selecting device will be moved to one of its several neutral or inoperative positions. Any other suitable operative connections from the selecting device 30 to an operating member on the steering post or located in other convenient position could be used.

54, 55, 56 and 57 represent toothed racks which are arranged to mesh with the teeth of the gear shifting wheels 7, 8, 9, 10, respectively. The rack 54 is arranged above and meshes with the teeth at the upper side of the wheel 7 and the rack 55 is arranged below and meshes with the teeth at the under side of the next wheel 8, these two racks being connected or formed on the two legs of a U-shaped piece which straddles the

shaft 5 and gear shifting wheels with its two legs in the respective planes of the wheels. The other pair of racks 56 and 57 are similarly joined in a U-shaped piece and arranged respectively above and below and 70 meshing with the other gear shifting wheels 9 and 10. The first double rack 54-55 is operatively connected to one of the gear shifting rods, as 2, of the change speed gear, and the other double rack 56-57 is operatively connected to the other gear shifting rod 1. If the gear shifting wheel 7 is turned in one direction by its co-operating dog 13 the double rack 54-55 will move in one direction and move the shifting rod 2 in one 80 direction, whereas if the second gear shifting wheel 8 is turned in the same direction the double rack 54-55 will be moved in the opposite direction and cause the opposite movement of the shifting rod 2. In a similar manner if the gear shifting wheel 9 is turned in one direction it will move the other double rack 56-57 and the shifting rod 1 in one direction, and if the fourth wheel 10 is turned in the same direction it 90 will cause an opposite movement of the double rack 56-57 and an opposite movement of the gear shifting rod 1. Thus one of the shifting rods 1 and 2 is adapted to be moved in opposite directions by movements of two of the gear shifting wheels in one and the same direction, and the other shifting rod is adapted to be moved in opposite directions by movements of the other two gear shifting wheels in the same direction. In other words, the gear shifting wheels are turned in the same direction to produce each of the opposite movements of the shifting rods. The racks 54-55 and 56-57 can be operatively connected to the shifting rods in any suitable way. As shown, the rack 54-55 is pivoted to a lever 58 which is fulcrumed at its upper end at 59 in the casing 4 and has a rounded lower end extending 100 into a seat in a collar or part 60 secured to the shifting rod 2. The other rack 56-57 is similarly pivoted to a lever 61 which is suitably fulcrumed at its upper end at 62 in the casing 4 and has a rounded lower end extending into a seat in a collar or part 63 secured to the other shifting rod 1. Figs. 6 and 17 show, respectively, the opposite movements of the rack 54-55 and lever 58 produced by turning the wheels 7 110 and 8 respectively in the same direction.

The shaft 5 and dog-carrier 12 are rocked for turning the gear shifting wheel after the selecting device has been set by suitable actuating means. Preferably, the dog-carrier is actuated through the medium of the clutch operating pedal and spring of the vehicle so that when the pedal is depressed to release the clutch in the usual manner the dog-carrier 12 is lowered to place one 120

of the dogs 13—16 in connection with its co-operating gear shifting wheel, and when the clutch pedal is returned, as by the usual spring to operate the clutch, the dog-carrier 5 is raised and rotates the gear shifting wheel to which the dog is engaged for operating one of the shifting rods of the change speed gear. In the construction shown, the clutch operating pedal is secured to the usual rock 10 shaft 64 which is operatively connected with the vehicle clutch. This shaft extends transversely through and is suitably journaled in the change speed gear casing A and is provided at one end with a rock 15 arm 65, see Figs. 2, 3 and 18—21, which is connected by an adjustable link 66 to an arm or lever 67 which is suitably fulcrumed at 68 on the casing 4. This lever 67 is provided with a laterally projecting stud or 20 roller 69 which extends into a slot 70 in an arm 71 secured to one end of the rock shaft 5. When the clutch pedal is depressed the arm 65 and lever 67 are raised, thereby 25 swinging the arm 71 upwardly and lowering the dog carrier 12 to the position shown in Fig. 6, in which one of the dogs 13—16 is adapted to engage the co-operating gear shifting wheel. When the pedal is released it is returned by the usual spring (not 30 shown) and swings the dog carrier upwardly and turns the gear shifting wheel. The arm 71 is preferably provided with a face 72 which is curved concentrically with the fulcrum of the lever 67 and forms 35 a continuation of the lower side of the slot 70 in the arm 71, so that when the clutch pedal is raised and the dog-carrier has been raised to the limit of its movement, the clutch pedal and the lever 67 40 can continue their movement to insure the proper operation of the clutch, the stud 69 co-operating with the face 72 acting as a lock to prevent the movement of the dog-carrier and gear shifting mechanism while 45 the clutch is in action. 73 indicates an adjustable screw or stop for engaging the arm 71 to limit the downward movement of the dog-carrier. 74 represents a spring which acts on the lever arm 65 in conjunction 50 with the usual clutch spring for producing the gear shifting action of the mechanism. This spring could, if desired, be made to entirely relieve the clutch spring of the duty of shifting the gears, or it 55 can be omitted and the clutch spring alone or other suitable spring used.

Means are preferably employed for locking the operating dogs for the gear shifting wheels in engagement with the wheels 60 when they have been moved into engagement therewith and for holding them in their normal or retracted positions to prevent accidental engagement of the dogs with or disengagement from the gear shifting wheels. For this purpose a locking 65

collar or ring 80 is loosely sleeved on the shaft 5 at one side of each of the gear shifting wheels 7—10. The locking rings serve to separate or space apart the gear shifting wheels. The locking rings are 70 held from turning with the shaft by suitable means, such for instance, as a finger 81 projecting from each ring into a socket 82 in the top of the casing 4, and each of the rings is provided with a radially projecting arm or part 83 provided at the side thereof facing the adjacent gear shifting wheel with ribs 84 which are curved concentrically with the shaft 5. The bolt 20 of each of the dogs 13—16 is provided with 80 a finger which extends at one side of the co-operating gear shifting wheel and is provided with correspondingly curved ribs 85 which are adapted to interlock with the ribs 84 on the locking ring. When one of 85 the dogs has been moved by its selecting cam into the notch 11 in the co-operating gear shifting wheel and the dog-carrier 12 is swung upwardly to turn the wheel, the two ribs 85 on the finger of the spring bolt 90 20 will straddle and interlock with the inner rib on the locking ring and the bolt will thus be retained in the notch 11 of the gear shifting wheel against the retracting action of the dog retracting spring 24, 95. The dog cannot be again disengaged from the gear shifting wheel except by swinging the dog-carrier down until the ribs on the bolt clear the ribs on the locking ring. If, however, the selecting device 30 is not 100 shifted from the position to which it was moved to engage the dog with the gear shifting wheel, the dog will not be disengaged from the wheel by the downward movement of the dog-carrier because the co-operating cam of the selecting device will 105 engage the end of the dog and prevent it from being withdrawn from the notch 11. Therefore, when one of the dogs has been engaged with its co-operating wheel it can 110 only be again disengaged by first shifting the selecting device to a neutral or a different dog operating position, and the clutch pedal can therefore be actuated at will 115 to operate the clutch in the usual manner without releasing the dog. In order to release the dog it is necessary to first move the selecting lever 52 and then depress the clutch pedal. When the selecting device 30 is shifted from the position 120 occupied by it when one of the dogs was moved into engagement with the gear shifting wheel, the co-operating cam is moved out of operative relation to the dog and when the dog-carrier is lowered by the depression of the clutch pedal the dog will 125 spring out of engagement with the gear shifting wheel as soon as its locking finger clears the rib on the locking ring. When the dog is retracted and the dog-carrier is 130

operated, the locking ribs on the finger of the spring bolt 20 will similarly coöperate with the outer rib on the locking ring 80, as shown in Fig. 12; and the dog will be thereby locked out of engagement with the coöperating gear shifting wheel.

In the operation of the vehicle, assuming the change speed gear and the operating mechanism to be in a neutral or inoperative position, the driver first sets the selecting lever 52 at the point indicated on the quadrant, for example, for the second forward speed. This moves the selecting device 30, as explained, to a position to place the cam 32 in operative relation to the gear operating dog 14. The clutch pedal is then depressed and released and this causes the operation of the dog-carrier 12 to cause the dog 14 to engage and turn the gear shifting wheel 8 in the manner described. The rotation of this wheel moves the rack 54—55 and the gear shifting rod 2, thereby placing the first forward speed gear train in action. The driver can then change to any other desired gear by first shifting the selecting lever 52 to the required point indicated and again operating the clutch pedal in a similar manner which will cause the operation of the required one of the gear shifting wheels 7—10 and produce the desired gear change. After setting the selecting lever 52 for a desired speed, it can be changed back to a neutral position or any other gear changing position before the clutch pedal is actuated without affecting any change in the mechanism other than the shifting of the selecting device 30. The pedal can be operated to release and apply the clutch at will while any speed gear is in action without changing the gearing, provided the selecting lever is not changed in the manner before explained.

I claim as my invention:

1. The combination with a change speed gear, of a plurality of gear-shifting members, actuating dogs for said members normally out of operative relation thereto, means for moving said dogs to actuate a selected gear-shifting member, a selecting device adapted to be set for placing any one of said dogs in operative relation to the coöperating gear shifting member, a manually operated device for setting said selecting device, and mechanical operating connections between said setting device and said selecting device.

2. The combination with a change speed gear, of a plurality of rotatable gear-shifting members, actuating dogs for said members normally out of operative relation thereto, means for oscillating said dogs to rotate a selected gear-shifting member, and a selecting device adapted to be set for placing any one of said dogs in operative relation to the coöperating gear-shifting member.

3. The combination of a plurality of rotatable gear shifting members arranged side by side, actuating dogs for said members normally out of actuating relation thereto, a movable dog-carrier on which the dogs are movable to and from operative relation to their respective gear-shifting members, a selecting device adapted to be set for placing any one of said dogs in operative relation to its coöperating gear-shifting member when said dog-carrier is operated, and means for oscillating said dog-carrier to rotate said gear-shifting members.

4. The combination of a plurality of gear-shifting members, actuating dogs for said members normally out of actuating relation thereto, means for oscillating said dogs, and a selecting device which is movable to different positions for placing different dogs in operative relation to their respective gear-shifting members when the dogs are oscillated in one direction, the oscillation of the dogs in the opposite direction actuating the selected gear-shifting member.

5. The combination of a plurality of gear-shifting members, actuating dogs for said members normally out of actuating relation thereto, an oscillatory dog-carrier for the dogs, a selecting device adapted to be set for placing any one of said dogs in operative relation to its coöperating gear-shifting member when the dog-carrier is oscillated in one direction, the opposite oscillation of the dog-carrier actuating the selected gear-shifting member, and a pedal controlling the actuation of said dog-carrier.

6. The combination of a plurality of gear-shifting members, actuating dogs for said members normally out of actuating relation thereto, an oscillatory dog-carrier for the dogs, a selecting device having actuating parts for said dogs and adapted to be set to place said parts in position to move any desired one of said dogs into operative relation to its coöperating gear-shifting member when the dog-carrier is oscillated in one direction, a manually operated device for setting said selecting device, and mechanical operating connections between said setting device and said selecting device, and means for oscillating said dog-carrier at will.

7. The combination of a plurality of gear-shifting members, actuating dogs for said members normally out of actuating relation thereto, an oscillatory dog-carrier for the dogs, a selecting device having an actuating cam for each dog and adapted to be set to place each of said cams in position to engage and move one of said dogs into operative relation to its coöperating gear-shifting member when the dog-carrier is oscillated in one direction, and means for oscillating said dog-carrier at will.

8. The combination with a change speed gear, of a plurality of gear-shifting mem-

- bers, manually operated means and mechanical operating connections therefrom to said gear-shifting members for actuating any desired one of said gear-shifting members, and means whereby the movement of different gear-shifting members in like direction produces movements in different directions of a movable part of the change speed gear.

10. 9. The combination with a change speed gear including an element which is movable in opposite directions, of a plurality of gear-shifting members, manually operated means and mechanical operating connections there- 15 from to said gear-shifting members for producing like movements of any desired one of said gear-shifting members, and means whereby the like movements of the different gear-shifting members produce opposite movements of said change speed gear element.

10. 9. The combination of a plurality of gear-shifting members, actuating dogs for said members normally out of actuating relation thereto, an oscillatory dog-carrier for the dogs, a selecting device having actuating parts for said dogs and adapted to be set to place said parts in position to move any desired one of said dogs into operative relation to its coöperating gear-shifting member when the dog-carrier is oscillated in one direction, a manually operated setting device for setting said selecting device and mechanical operating connections between 25 said setting device and said selecting device, and means for oscillating said dog-carrier at will.

11. The combination of a plurality of gear-shifting wheels arranged side by side, 40 actuating dogs for said wheels normally out of actuating relation thereto, a dog-carrier for said dogs adapted to oscillate about the axes of said wheels, a selecting device adapted to be set for placing any one of said 45 dogs in actuating relation to its coöperating gear-shifting wheel when said dog-carrier is oscillated in one direction, means for oscillating said dog-carrier, and a change speed gear controlled by said gear-shifting wheels.

50. 12. The combination of a plurality of gear-shifting wheels arranged side by side, actuating dogs for said wheels normally out of actuating relation thereto, a dog-carrier for said dogs adapted to oscillate about the 55 axes of said wheels, a selecting device which is provided with cams for said dogs and is movable transversely of the planes of rotation of said wheels for placing said cams into position to move one of said dogs into 60 actuating relation to its coöperating wheel when said dog-carrier is oscillated in one direction, and means for oscillating said dog-carrier.

13. The combination of a plurality of 65 gear-shifting wheels arranged side by side,

actuating dogs for said wheels normally out of actuating relation thereto, a dog-carrier for said dogs adapted to oscillate about the axes of said wheels, a selecting device which is provided with a cam for each of said dogs 70 and is movable transversely of the planes of rotation of said wheels for placing each of said cams into position to move one of said dogs into actuating relation to its coöperating wheel when said dog-carrier is oscillated in one direction, said dogs and said cams being arranged in corresponding staggered relation, and means for oscillating said dog-carrier.

14. The combination of a plurality of 80 gear-shifting wheels arranged side by side, actuating dogs for said wheels normally out of actuating relation thereto, a dog-carrier for said dogs adapted to oscillate about the axes of said wheels, a selecting device which is provided with a cam for each of said dogs 85 and is movable transversely of the planes of rotation of said wheels for placing each of said cams into position to move one of said dogs into actuating relation to its coöperating wheel when said dog-carrier is oscillated in one direction, said dogs and said cams being arranged in corresponding staggered relation and said cams being located closer together than the coöperating portions of 90 said dogs, and means for oscillating said dog-carrier.

15. The combination of a plurality of 95 gear-shifting wheels arranged side by side, actuating dogs for said wheels normally out of actuating relation thereto, a dog-carrier for said dogs adapted to oscillate about the axes of said wheels, a selecting device adapt- 100 ed to be set for placing any one of said dogs in actuating relation to its coöperating gear-shifting wheel when said dog-carrier is oscillated in one direction, means for oscillating said dog-carrier, a rack moved in one direction by one of said wheels, a rack moved in the opposite direction by another of said 105 wheels, and means operated by said racks.

16. The combination of a plurality of 110 gear-shifting wheels arranged side by side, actuating dogs for said wheels normally out of actuating relation thereto, a dog-carrier for said dogs adapted to oscillate about the axes of said wheels, a selecting device adapt- 115 ed to be set for placing any one of said dogs in actuating relation to its coöperating gear-shifting wheel when said dog-carrier is oscillated in one direction, means for oscillating said dog-carrier, a double rack having a toothed engagement with one of said 120 wheels at one side of its axis and with another of said wheels at the opposite side of its axis, and means operated by said rack.

17. The combination of a plurality of 125 gear-shifting members, actuating dogs for said members normally out of actuating engagement therewith, an oscillatory dog-car- 130

rier for said dogs, a selecting device adapted to be set for moving any one of said dogs into actuating engagement with its coöperating gear-shifting member when said dog-carrier is oscillated in one direction, means for oscillating said dog-carrier, and means for locking the selected dog in engagement with its coöperating gear shifting member.

18. The combination of a plurality of gear-shifting members, actuating dogs for said members normally out of actuating engagement therewith, an oscillatory dog-carrier for said dogs, a selecting device adapted to be set for moving any one of said dogs into actuating engagement with its coöperating gear-shifting member when said dog-carrier is oscillated in one direction, means for oscillating said dog-carrier, and means for retaining the selected dog in engagement with its coöperating gear shifting member so long as said selecting device remains in operative relation to said dog.

19. The combination of a plurality of gear-shifting members, actuating dogs for said members normally out of actuating engagement therewith, an oscillatory dog-carrier for said dogs, a selecting device adapted to be set for moving any one of said dogs into actuating engagement with its coöperating gear-shifting member when said dog-carrier is oscillated in one direction, means for oscillating said dog-carrier, and means for locking the selected dog in engagement with its coöperating gear shifting member and for locking the remaining dogs out of engagement with their coöperating gear shifting members.

20. The combination of a plurality of gear-shifting members, actuating dogs for said members normally out of actuating engagement therewith, an oscillatory dog-carrier for said dogs, a selecting device adapted to be set for moving any one of said dogs into actuating engagement with its coöperating gear-shifting member when said dog-

carrier is oscillated in one direction, means for oscillating said dog-carrier, a locking device for each of said dogs, and parts on said locking device and said dog adapted to interlock for retaining the dog in engagement with its coöperating gear shifting member.

21. The combination of a plurality of gear-shifting members, actuating dogs for said members normally out of actuating engagement therewith, an oscillatory dog-carrier for said dogs, a selecting device adapted to be set for moving any one of said dogs into actuating engagement with its coöperating gear-shifting member when said dog-carrier is oscillated in one direction, means for oscillating said dog carrier, a locking device for each of said dogs, and parts on said locking device and said dog adapted to interlock in one position for retaining the dog in engagement with its coöperating gear-shifting member, and to interlock in another position for holding the dog out of engagement with the gear-shifting member.

22. The combination of a plurality of gear-shifting members, a selecting device adapted to be moved to different positions, actuating means controlled by said selecting devices for actuating one or another of said gear-shifting members, a clutch pedal for operating a clutch and said actuating means, and lost motion operative connections between said pedal and said actuating means constructed to allow the movement of the pedal to continue for operating the clutch after the completion of and initial movement of the pedal sufficient to actuate said actuating means.

Witness my hand this 3rd day of April, 1915.

WILLIAM H. ADSIT.
